UNITED STATES PATENT OFFICE.

LEROY R. MORRIS, OF LONGBEACH, CALIFORNIA.

AUTOMATIC CHIMNEY-SWEEP.

1,075,593.

Specification of Letters Patent. Patented Oct. 14, 1913.

Application filed December 11, 1911. Serial No. 665,068.

To all whom it may concern:

Be it known that I, LEROY R. MORRIS, a citizen of the United States, residing at Longbeach, Los Angeles county, California, 5 have invented a new and useful Automatic Chimney-Sweep, of which the following is a specification.

My invention relates to the construction of an apparatus for cleaning flues and chimneys.

The object of the invention is to provide a device which will utilize the shifting of air currents as a motive power and which will at all times automatically keep the 15 chimney clean and free from obstruction. The means by which these beneficial results are attained is set forth in the accompanying drawings, in which—

Figure 1 is a side elevation of my chimney cleaner and chimney in which it is used. Fig. 2 is a front elevation of the parts shown in Fig. 1. Fig. 3 is a transverse section taken at *a—a* in Fig. 1. Fig. 4 is a side elevation of a series of chimneys, each 25 containing a cleaner, and all operated in unison by a single wind vane. Figs. 5 and 6 are front and side views, respectively, of sections of shafting utilized in my device and are intended to especially illustrate the 30 construction of the couplings connecting the various pieces of shafting.

Throughout the several views like characters indicate like parts, and referring to the details of construction—6 is a chimney 35 upon which my device is used. 7 is a shafting supported vertically in the center of said chimney. This shafting is ordinarily made in one piece as shown in Fig. 1 and extends above the top of the said chimney. 40 Where conditions require, however, the shaft is made in sections and united with a suitable joint. One type of joint adaptable to this purpose is shown in Fig. 5 and in Fig. 6. In this joint a fork 8 on one end 45 of the shaft 7 engages recesses 9 in the adjacent end of the next piece of shafting. 10 is a wind vane attached to the upper end of said shafting 7.

11 is a supporting bearing on the top of the chimney. 50

12 indicates guide wheels attached to the shaft 7 at intervals to keep the shaft in the center of the chimney.

13 is a pin used to attach said wheel to said shaft. 14 refers to non-combustible bristles or metallic scrapers attached to said shaft in one or more vertical rows. Each of these bristles is long enough to remain in contact with the wall of the chimney during an entire revolution of the shaft. 55

In Fig. 4 sprocket wheels 17 are attached to the shaft 7 and chains 18 pass over these and like sprockets 19 on other shafts 7 in adjacent chimneys. In this manner several shafts are made to revolve in unison and all 60 may be operated by a single vane 10. 65

In use every change in the direction of the wind causes the vane to revolve a like amount. The vane being rigidly attached to the vertical shafting turns the shaft and 70 the bristles move along the walls of the chimney, dislodging all particles of soot and keeping the chimney brushed clean at all times. A chimney equipped with this 75 device will remain clean and thoroughly efficient without further attention.

Having thus described my invention, what I claim as new and desire to secure by Letters Patent is:—

In a chimney cleaning apparatus: the 80 combination of a chimney; a vertical shafting centrally suspended within said chimney; means for supporting said shafting; a wind vane rigidly attached to the top end of said shafting; guide wheels attached to said 85 shaft at intervals within said chimney; and non-combustible bristles arranged longitudinally along said shafting adapted to come in contact with all portions of said flue while said shaft is being revolved one complete revolution. 90

LEROY R. MORRIS.
